UNITED STATES PATENT OFFICE.

CHARLES S. PALMER AND DEAN PALMER, OF SARANAC LAKE, NEW YORK.

PENCIL-SHARPENER.

1,267,586.

Specification of Letters Patent. Patented May 28, 1918.

Application filed January 29, 1917. Serial No. 145,114.

To all whom it may concern:

Be it known that we, CHARLES S. PALMER and DEAN PALMER, citizens of the United States, residing at Saranac Lake, counties 5 of Essex and Franklin, respectively, State of New York, have invented a certain new and useful Improvement in Pencil-Sharpener, of which the following is a specification, reference being had therein to the accompanying drawings.

Our invention has for its object an improved holder or clip which is designed to be used in connection with lead pencils or the like and to be used as a holder and sharpener for the same. The device preferably consists of a spring metal split band and of a pocket engaging portion secured at one end to the band and provided at the free end with a lead sharpening device. 15 The pocket engaging clip is so arranged and combined with the lead sharpening device that it operates both as a means for holding the pencil in the pocket of the user, and as a means for sharpening the pencil and for 20 guiding it when being sharpened so that the pencil lead or other like material may be quickly and readily brought to the desired point.

Our invention will be fully understood 30 when taken in connection with the accompanying drawings and the novel features thereof will be pointed out and clearly defined in the claims at the close of this specification.

35 In the drawings, Figure 1 is a view of a paper rolled pencil provided with a device embodying our invention.

Fig. 2 is a front view in perspective of a pencil attachment embodying our invention.

40 Fig. 3 is a top plan view of the device.

Fig. 4 is a vertical section enlarged of the sharpener.

Fig. 5 is a view showing the holder in use as a lead sharpening device.

45 Having reference to the drawings there is shown a pencil 11 of the paper rolled type to which is secured a clip or holder 12 embodying our invention. The holder 12 consists preferably of a split band of spring

50 metal 13, which is adapted to surround the pencil as shown in Fig. 1, and is provided at one of its split ends with an inturned portion 14, which extends toward the center of the band 13 and is sharpened at its inner edge 15. In order that the sharpened end 15

55 will not normally engage with the pencil, to

which the holder is applied, that part of the band 13, which is adjacent the inturned portion 14, is bent outwardly somewhat as shown at 16.

The band, hereinabove described, is particularly adapted to be used on paper rolled pencils, for the knife edge 15 may be employed to sever a paper strip of the pencil to enable the pencil to be sharpened. Another form of band however may be equally well employed in connection with the combined pocket engaging portion and lead sharpening device which will now be described.

At 17 is shown a pocket engaging portion which is preferably integral with the band 13 and comprises a shank 18 and lead sharpening device 19. The shank 18 projects outwardly from the lower edge of the band 75 13 so that a space is formed between the pencil and the shank at its upper end. It then curves downwardly as shown, and inclines toward the side of the pencil, to which the holder is applied, until it is in contact 80 with it near its lower end, as shown at 20. The shank then curves outwardly and at its lower end is provided with a cone shaped lead sharpening device 19. The shank is preferably of spring metal, being formed 85 as described so that it will readily engage the outer edge of the pocket of the user when the pencil is inserted into the pocket.

The lead sharpener 19 is preferably integral with the shank 18 and consists of a 90 strip of metal 21 which is attached to one side of the lower end of the shank and is formed in a cone-shaped spiral as shown. The inner portion 22 of the spiral is so arranged that the opening at its upper end 95 is somewhat greater than the diameter of the lead of a pencil, while that at its lower end is relatively small, preferably of the size shown. The inner end 23 of the spiral metal strip 21 is sharpened to form a knife 100 edge which is adapted to engage with and sharpen the lead of a pencil inserted within the spiral portion 22 in a manner herein-after to be described.

In order that the lead of the pencil may 105 be inserted within the sharpener 19 and readily and quickly sharpened to the desired point, the shank 18 of the pocket engaging portion 17 is so arranged and constructed that it acts as a guide for the pencil 110 while the lead is being sharpened. For this purpose, the shank 18 is formed with a con-

cave surface 24, which is adapted to engage a portion of the periphery of the pencil and operate as a guide against which the pencil may be rotated when the clip is being used 5 as a sharpener, as is clearly shown in Fig. 5. The lower end of the shank 18 is so arranged that the sharpener 19 is directly in line with the axis of the pencil. We regard this feature of our invention as important 10 for by the use of the guiding means described, the lead of a pencil may be readily sharpened without becoming broken during the sharpening process as would otherwise be apt to be the case.

15 It will be noted from the above, that when the device is being used as a holder, the sharpener 19 takes the place of a button or ball on the end of the pocket engaging portion and aids materially in guiding the pocket engaging portion over the outer 20 edge of the pocket; and when the holder is being used as a sharpener the shank of the pocket engaging portion serves as a guide for the pencil as it is being sharpened. The band 13 of the holder forms 25 not only a means for attaching it to the pencil but also serves as a handle for holding the clip when it is being used as a pencil sharpening device. The device thus affords a convenient means for holding a 30 pencil in the pocket of the user and for sharpening the pencil when desired.

What we claim is:

1. The improved pencil attachment comprising a band for attachment to a pencil, a spring shank portion connected with the band and adapted to extend along side of the pencil whereby the device may coöperate with a pencil held therein for attachment to a pocket, and a pencil sharpener on 40 the opposite end of the shank from that to

which the band is attached, the shank portion being concave transversely to form a guide for a pencil.

2. A pencil attachment comprising a band 45 for attachment to a pencil, a spring shank portion connected with the band which extends along side of the pencil and coöperates therewith for attachment to a pocket, the shank being transversely curved in such 50 manner as to present a substantially concave side toward the pencil, and a pencil sharpener on the opposite end of the shank from that to which the band is attached, said sharpener consisting of a cone-shaped 55 spiral sharpened at its inner edge, the axis of the cone being substantially parallel with the axis of the band, the concave face of the shank engaging the pencil when the point of the pencil is inserted in the sharpener. 60

3. A pencil attachment comprising a band for attachment to a pencil, a spring shank portion connected with the band which extends along side of the pencil and coöperates therewith for attachment to a pocket, the shank being transversely curved in such 65 manner as to provide a substantially concave face toward the pencil, and a pencil sharpener on the opposite end of the shank 70 from that to which the band is attached, said sharpener consisting of a cone-shaped spiral sharpened at its inner edge, the axis of the cone being substantially parallel with the axis of the band, the side of the cone 75 which is adjacent the pencil flaring away from the side of the pencil.

In testimony whereof we affix our signatures.

CHARLES S. PALMER.
DEAN PALMER.
